[57] ABSTRACT

A double soap bar comprising a first soap bar having a cavity formed therein and a second soap bar inserted within the larger soap bar, forming a single unit for wrapping purposes.

FIG. 1

FIG. 2

FIG. 3

FIG. 4

DOUBLE SOAP BAR

BACKGROUND OF THE INVENTION

Hotels, motels and inns provide soap for their guests wherein the soap is formed in small bars. Generally the hotels, motels and inns provide two different sizes of soap bars, a small facial bar and a larger bar for the bath. People prefer the larger bar for the bath as it is easier to handle and the smaller bar for facial use. This has caused the hotel to expend monies for two different bars of soap, each individually wrapped. Furthermore, only a small portion of the soap is generally used, therefore there is considerable waste and the additional cost of wrapping each bar individually is a waste of money to the hotel owner.

SUMMARY OF THE INVENTION

This invention relates to soap and particularly to a bar soap which is formed with a smaller bar insert disposed therein. The use of a smaller bar within the larger bar lessens the amount of soap actually wasted and also provides for a single wrapping rather than two individual wrappings.

An object of this invention is to provide a first bar of soap having a cavity formed therein and a second bar of soap disposed therein.

A further object of this invention is to provide a double bar of soap wherein the amount of soap used to form the smaller bar is substantially reduced from the larger bar which is economical to manufacture.

A further object of this invention is to provide a double bar of soap wherein a single wrapping is utilized thus saving money on wrapping costs.

Another object of this invention is the provision of a bar of soap which is formed from less soap yet is of sufficient bulk to permit it to be readily grasped by the user.

Yet another object of this invention is the provision of a double bar of soap, one mounted within the other, wherein considerable saving of soap is provided, less wrapping is required, it is simple and economical of manufacture.

These objects and other features and advantages become more readily apparent upon reference to the following description when taken in conjunction with the appended drawings.

In the drawings as hereinafter described, a preferred embodiment of the invention is illustrated, however various modifications can be made thereto without departing from the true spirit and scope of the invention.

BRIEF DESCRIPTION OF THE DRAWINGS

FIG. 1 is a perspective view of the double soap bar of this invention;

FIG. 2 is a top plan view thereof;

FIG. 3 is a cross-sectional view taken along the lines 3 — 3 in FIG. 2; and

FIG. 4 is a perspective view of a modified embodiment of this invention.

DESCRIPTION OF THE PREFERRED EMBODIMENT

Referring now to the drawings, the double soap bar of this invention is disclosed generally at 10 in FIGS.

15 1-3. The double bar comprises a first bar 11 having a second bar 12 inserted in a cavity 13 formed therein.

Referring to FIGS. 2 and 3, the first bar 11 is formed with an upstanding annular flange 14 projecting above a surface thereof of sufficient height to form the cavity 13 for holding the second bar 12. The outer surface 15 of the flange 14 is substantially on the same plane as the outer surface 16 of the second bar 12 when the latter is disposed within the cavity 13.

The second bar 12 is of such a size so that when the 25 bar 12 rests within the cavity 13 of the first bar 11, there is a gap 17 between the inner wall 18 of flange 14 and the outer wall 21 of the second bar 12, thus rendering the second bar 12 easily removable from the first bar 11.

The amount of soap saved from the formation of the 30 cavity 13 is substantially the same amount of soap that is utilized in the formation of the second bar 12. Thus there is a savings on the total amount of soap used as opposed to having two separate full bars of soap.

The bottom wall of the cavity may be concaved 35 slightly, thus permitting the user to easily remove the second bar by merely pushing thereon proximate the periphery thereof thus causing the bar 12 to rock and the edge opposite to project slightly above the top surface of the first bar.

40 The soap bars used can either be of the circular shape as depicted in FIGS. 1-3 or of the standard rectangular shape as depicted in FIG. 4, or of a combination thereof without departing from the true spirit and scope of the invention.

45 I claim:

1. A double soap bar comprising:
a first bar formed into a predetermined shape, and a second bar disposed within the first bar.

2. A double soap bar as defined in claim 1 wherein 50 said first bar has a peripheral flange projecting upwardly from a surface thereof to form a cavity in which said second bar is disposed.

3. A double soap bar as defined in claim 2 wherein said surface within said cavity is concaved.
